UNITED STATES PATENT OFFICE

2,585,142

SPORT SHIRT OR LIKE GARMENT

Joseph I. Levitt, Miami Beach, Fla.

Application July 13, 1950, Serial No. 173,496

2 Claims. (Cl. 2—105)

1

This invention relates to a novel sport shirt or like body garment of the vest or sleeveless and collarless type.

The object of the present invention is to provide a garment of the above kind which comprises back and front sections joined by shoulder seams and cut out to form side arm openings and a large neck opening at the juncture of said sections through which the head may pass, the side edge portions of the back section being adapted to overlap those of the front section at the sides of the garment below the arm openings, and spaced means being provided to separably connect each side edge of the back section to the adjacent side of the front section directly under the arm opening and at the bottom of the garment, said sections being free of connection with each other between said spaced means, so that the side edge portions of the back section between said spaced means will act to scoop air into the garment at the sides of the latter for ventilating and cooling purposes, upon forward travel of the wearer.

In the accompanying drawing:

Figure 1 is a front elevational view of a garment embodying the present invention, as it appears when being worn.

Figure 2 is a rear elevational view thereof.

Figure 3 is an enlarged horizontal section taken on the line 3—3 of Figure 1.

Referring in detail to the drawing, 5 indicates a back section and 6 indicates a front section. These sections are preferably made of suitable woven textile fabric such as commonly used in the manufacture of sport shirts, and they are permanently joined by shoulder seams 7. The sections 5 and 6 are also cut out to form side arm openings 8 and a large neck opening 9 at the juncture of said sections between the shoulder seams.

The side edge portions 10 of the back section are adapted to overlap the side edge portions 11 of the front section at the sides of the garment below the arm openings, and spaced means are provided, as at 12 and 12a to separably connect each side edge of the back section to the adjacent side of the front section. This leaves the sec-

2

tions free of connection with each other between the means 12 and 12a at each side of the garment, so that the edge portions of the back section between such means may bulge outwardly and act to scoop air into the garment at the sides of the latter, for ventilating and cooling purposes, upon forward travel of the wearer. As shown, the means 12 and 12a may include projecting tabs 13 and 14 on the side edges of the back section provided with buttonholes to receive buttons 15 and 16 attached to the front section.

Having described the invention, what is claimed as new is:

15. 1. A collarless and sleeveless shirt comprising front and back sections permanently joined by shoulder seams and cut out to provide side arm openings and a large neck opening between the shoulder seams at the juncture of said sections, the side edge portions of the back section being overlapped upon the side edge portions of the front section at the sides of the shirt, and spaced means separably connecting the side edges of the back section to the adjacent sides of the front section directly under the arm openings and at the bottom of the shirt, the sections being free of connection with each other between said spaced means so that the side edge portions of the back section bulge outwardly between said spaced means to scoop air into the garment at the sides of the latter upon forward travel of the wearer.
20. 2. A shirt according to claim 1, wherein said spaced means include projecting tabs on the side edges of the back section, and means to detachably connect said tabs to the front section.

JOSEPH I. LEVITT.
